WHEEL

Richard L. Rader, 325 Termino,
Long Beach, Calif. 90814

Filed Oct. 9, 1964, Ser. No. 82,123

Term of patent 7 years

(Cl. D14—30)

FIG. 1 is a front elevational view of a wheel showing my new design;

FIG. 2 is a cross-section through the wheel taken on line 2—2 of FIG. 1; and

FIG. 3 is a perspective view of the wheel shown in FIG. 1.

The dominant features of my design reside in the portions shown by means of full lines in the drawings.

I claim:

The ornamental design for a wheel, substantially as shown and described.
